UNITED STATES PATENT OFFICE.

MARTIN D. WOOD, OF KANSAS CITY, MISSOURI.

DESIGN FOR A BADGE.

SPECIFICATION forming part of Design No. 22,796, dated September 26, 1893.

Application filed May 18, 1893. Serial No. 474,714. Term of patent 7 years.

To all whom it may concern:

Be it known that I, MARTIN D. WOOD, a citizen of the United States, residing at Kansas City, in the county of Jackson and State 5 of Missouri, have invented and produced a new and original Design for a Badge; and I do declare the following to be a full, clear, and exact description of the same, reference being had to the accompanying drawings, forming 10 a part thereof.

My invention relates to a new and original design for a badge, of which the following is a specification, reference being had to the accompanying drawings, which form a part 15 thereof.

Figure 1, is a front view of the badge. Fig. 2, is an edge view of the same, the two views being deemed necessary to fully illustrate the design.

20 The leading features of the design are, an upper plate with plain surface, having a filigree border and scroll on top. Suspended to the upper plate is a lower plate suitably divided into four equal parts by serrated lines

converging from each corner toward the center, thereby forming four triangular divisions of the plate; each triangle has a dotted surface with a lily bud in each corner of the base of each triangle pointing toward the center. Each triangle has a milled or raised 25 border and in the center of the base of each triangle appears an open scroll. The common center of these four triangles is provided with an ornament consisting of a crown through which passes a sword and staff, both 30 sword and staff pointing upward, but crossing each other, the staff being surmounted by a star on its upper point.

What I claim is—

The design for a badge substantially as 40 shown and described.

In testimony whereof I have affixed my signature in presence of two witnesses.

MARTIN D. WOOD.
